CLAIM

The ornamental design for a drain plug, as shown and described.

DESCRIPTION

FIG. 1 is a perspective view of a drain plug showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a bottom perspective view thereof.

FIG. 9 is an enlarged detail view of area 9 shown in FIG. 2; and,

FIG. 10 is a front perspective view, shown in an exploded state.

The broken lines in the drawings depict portions of the drain plug that form no part of the claimed design.
